NOZZLE

Henry Huss, Greenwich, Conn.

Application December 28, 1935, Serial No. 56,471

5 Claims. (Cl. 299—120)

This invention relates to atomizing nozzles or tips, and provides a nozzle or tip which is particularly well adapted for use in oil burners in which the oil is delivered under high pressure.

5 One of the objects of my invention is the provision of a nozzle construction embodying a nozzle body containing a member equipped with an ejection orifice and with a swirl chamber, a distributor head and a threaded stem, my improved construction providing for accurate positioning of these members in the nozzle body and relatively to each other.

In devices of this character dimensions are very small, and for full efficiency of the device it is necessary that the parts shall be exactly positioned. Also in such devices it is exceedingly difficult to prevent slight eccentric motion of the threaded stem, which is likely to cause misalignment. This is avoided in the present construction in that the member which is equipped with an ejection orifice and with a swirl chamber "floats", i. e., is capable of slight lateral movement in the nozzle body so as to permit the distributor head properly to seat itself regardless of any eccentricity in the threaded stem. If desired the distributor head too may "float" thereby further insuring exact positioning of the distributor or distributor head in relation to the swirl chamber and ejection orifice.

30 In the accompanying drawing I have shown two embodiments of my invention:

Fig. 1 showing in part sectional elevation one embodiment of my invention; and

Fig. 2 a modification.

35 Referring to the drawing in detail and first of all to Fig. 1, the nozzle body, designated 1, is provided with a discharge orifice 2 at its front end, shown as at the apex of a flaring recess 3.

In the front end of the bore of the nozzle body 40 1 is a member 4. This member is a loose fit in the nozzle body as will be seen from the drawing, where a space 5 is shown between the member and the walls of the bore of the nozzle body. It is to be understood that the outside diameter of the 45 member 4 is several thousandths of an inch less than the inside diameter of the bore of the nozzle body which receives it, to insure provision for lateral play of the member in the nozzle body.

The space 5 shown in the drawing is somewhat exaggerated for purposes of illustration.

The member 4 at its rear end is beveled or recessed as shown at 6, this recess merging into a swirl chamber 8 and an ejection bore 7 extending longitudinally of the setting member.

55 Threaded into the nozzle body is a screw stem

8 the lower end of which is beveled as shown at 9 to correspond in form to the recessed face of the member 4. This beveled stem-end is provided with tangential grooves 10 which conduct and direct the oil, or other material to be atomized, 5 to the swirl chamber. This beveled and grooved stem-end constitutes a distributor or distributor head.

The threaded portion of the stem 8 and which I will designate 11 is somewhat enlarged in diameter with respect to the remainder of the stem. The stem is provided with a longitudinal and cross-bore 12 for the passage of the material to be atomized from a suitable source of supply.

It will now be apparent from the foregoing that 15 by making the member 4 a loose fit, i. e., a floating fit in the nozzle body the distributor or distributor head will always be brought into precise and exact seating position in the recessed face of the member 4, regardless of any eccentric motion of the stem 8 such as referred to at the outset of this description. In other words, when the stem 8 is screwed inwardly of the nozzle body to bring the distributor into engagement with the recessed face 6 of the member 4, the latter 20 being a floating fit in the bore of the nozzle body, is free to be displaced laterally sufficiently to insure seating of the distributor head uniformly 25 against the recessed face of the member 4, irrespective of any slight eccentric movement of the 30 stem. Not only does this insure discharge of the material being atomized in a perfect cone, but it insures that the material of the cone will be uniform. In the burning of oil, using nozzles of the general type herein described, improper 35 seating of the distributor head in the recessed face of the member 4 allows more oil to move toward the swirl chamber along one side of the distributor head than the other, and this is reflected in the discharging material and as the 40 same is burned, atomization not being uniform and the flame spotty and unsatisfactory.

The embodiment of my invention illustrated in Fig. 2 is quite similar to that just described. In this construction the nozzle body 1' is provided 45 with a discharge orifice 2'. Located in the bore of the nozzle body is a member 4' corresponding to the member 4 of Fig. 1, this member, as illustrated having a floating fit in the nozzle body core.

14 designates a floating distributor or distributor head located in the nozzle body above the member 4', the end of this distributor being beveled or tapered as shown at 9' to fit the recessed rear face 6' of the member 4'. The recess in the rear face of the member 4' merges into a swirl 55

chamber 3' and ejection orifice 7' in the member 4'.

8' designates a threaded stem similar to the stem 8 of Fig. 1 in that it is provided with longitudinal channels 12', but in this embodiment of my invention the stem is not integral with the distributor. In other words, the member 4' and distributor 14 in this construction are free to have lateral movement relatively to each other 10 as well as relatively to the stem 8'.

It will now be apparent that when the stem 8' is screwed inwardly of the nozzle body into engagement with the distributor, the lateral play permitted so far as the distributor and the member 4' are concerned will promote precise seating of the tapered face of the distributor in the recessed face of the member 4' despite any eccentric motion of the screw stem such as above referred to, a condition which as above pointed out 20 is not only desirable but essential.

While as above explained my improved construction provides for precise and exact alignment of the parts of the nozzle, it also provides another advantage in that in the construction of Fig. 1 the member 4 may be readily replaced at the minimum of expense, while in the construction of Fig. 2 any of the parts can be replaced independently of the others.

What I claim is:—

30 1. An atomizing nozzle comprising a body having a discharge orifice, a floating member in said body, adjacent said discharge orifice, provided with an ejection orifice communicating with said discharge orifice and with a tapered swirl chamber 35 to the rear of said ejection orifice, said floating member being further provided with a tapered surface at the rear of said swirl chamber, a distributor in the said nozzle body having a tapered face corresponding in form to and fitting 40 against said tapered surface, said distributor face being provided with whirl-producing grooves communicating with said swirl chamber, and a screw stem in the body behind said distributor for coaction with the distributor, said stem being 45 provided with a channel for the passage of the material to be atomized along said stem to said distributor.

2. An atomizing nozzle comprising a body having a discharge orifice, a floating member in said body, adjacent said discharge orifice, provided with an ejection orifice communicating with said discharge orifice and with a tapered swirl chamber 50 to the rear of said ejection orifice, said floating member being further provided with a tapered surface at the rear of said swirl chamber, a distributor in the said nozzle body having a tapered face corresponding in form to and fitting 55 against said tapered surface, said distributor face being provided with whirl-producing grooves communicating with said swirl chamber, and a screw stem in the body behind said distributor for coaction with the distributor, said stem being provided with a longitudinal channel for the passage of the material to be atomized along said stem to said distributor, said first mentioned member and said distributor being free to have lateral play 60 with respect to said stem.

provided with a longitudinal channel for the passage of the material to be atomized along said stem to said distributor.

3. An atomizing nozzle comprising a body having a discharge orifice, a floating member in said body, adjacent said discharge orifice, provided with an ejection orifice communicating with said discharge orifice and with a tapered swirl chamber to the rear of said ejection orifice, said floating member being further provided with a tapered surface at the rear of said swirl chamber, a floating distributor in the said nozzle body having a tapered face corresponding in form to and fitting against said tapered surface, said distributor face being provided with whirl-producing grooves communicating with said swirl chamber, and a screw stem in the body behind said floating distributor for coaction with the distributor, said stem being provided with a longitudinal channel for the passage of the material to be atomized along said stem to said distributor.

4. An atomizing nozzle comprising a body having a discharge orifice, a member in said body, adjacent said discharge orifice, provided with an ejection orifice communicating with said discharge orifice and with a tapered swirl chamber to the rear of said ejection orifice, said member being further provided with a tapered surface at the rear of said swirl chamber, a distributor in the said nozzle body having a tapered face corresponding in form to and fitting against said tapered surface, said distributor face being provided with whirl-producing grooves communicating with said swirl chamber, and a screw stem in the body behind said distributor for coaction with the distributor, said stem being provided with a longitudinal channel for the passage of the material to be atomized along said stem to said distributor.

5. An atomizing nozzle comprising a body having a discharge orifice, a member in said body, adjacent said discharge orifice, provided with an ejection orifice communicating with said discharge orifice and with a tapered swirl chamber to the rear of said ejection orifice, said member being further provided with a tapered surface at the rear of said swirl chamber, a distributor in the said nozzle body having a tapered face corresponding in form to and fitting against said tapered surface, said distributor face being provided with whirl-producing grooves communicating with said swirl chamber, and a screw stem in the body behind said distributor for coaction with the distributor, said stem being provided with a longitudinal channel for the passage of the material to be atomized along said stem to said distributor, said first mentioned member and said distributor being free to have lateral play with respect to said stem and relatively to each other.

HENRY HUSS.
